APPARATUS FOR PRODUCING ELECTRIC SPARKS FOR USE IN SPECTRUM ANALYSIS

Heinrich Kaiser, Jena, Germany, assignor to the firm of Carl Zeiss, Jena, Germany

Application April 8, 1939, Serial No. 266,919
In Germany April 11, 1938

6 Claims. (Cl. 176—8)

The present invention concerns apparatus for producing sparks in spectrum analysis, which have a plurality of spark gaps connected in series to each other and to an energy accumulator to be discharged. Apparatus of this kind play an important part in spectro-analytic tests of materials. In a known embodiment of a spark producer, one spark gap, the electrodes of which are constituted by specimens of the material to be examined, is connected in series to the two spark gaps of a rotary interrupter. Other embodiments are known which have two series-connected spark gaps and in which the spectral lines of one spark gap are compared to those of the other. To obtain an unobjectionable working of these known apparatus, it is necessary to provide that the series-connected gaps spark over simultaneously or successively at very short intervals (of for instance 10^{-8} to 10^{-6} seconds). It is necessary, therefore, that, at all gaps, the necessary sparking voltage is arrived at nearly simultaneously and that, moreover, all gaps have at the same time the electrons for starting the sparking. If not, it may happen that sparking takes place in the one gap and the discharge is then interrupted on account of the next gap not being conductive as yet. The sparks are thus made to flicker, and they start at irregular intervals and occasionally not at all, even when use is made of the known mechanical control by means of interrupters in the form of rotary spark gaps. This difficulty has generally been overcome so far by radiating the spark gaps with ultra-violet rays or a radium preparation. This method is, however, restricted in effectiveness and naturally adds to the cost of the entire apparatus. Ensuring a reliable sparking in the gaps by means of very high voltages is rather expensive as well. It has also been taken into consideration that the charging voltage of the energy accumulator, which produces the sparking in the gaps, is apportioned to these gaps inversely to their capacities. The high-capacity spark gaps receive, accordingly, only a small portion of the charging voltage, so that the breakdown field-strength is eventually not arrived at.

The invention provides that in apparatus for producing single sparks or series of sparks and having a plurality of spark gaps connected in series and traversed by the same discharge current, at least part of these gaps is bridged by conducting means. For bridging, use can be made either of resistances, condensers or choking coils producing an impedance of approximately 10^5 to 10^7 ohms, or of a plurality of such ele-

ments connected in series or in parallel. It is preferable, however, to use a high ohmic resistance producing the said impedance. The most convenient method consists in bridging, if possible all spark gaps except one by reactances, so that nearly the entire charging voltage is at this one unbridged spark gap. When a sparking has taken place in this one gap, the discharge cannot be interrupted, because a weak discharge current can flow through the bridging resistances of the other spark gaps. After the sparking, the voltage decreases at the unbridged spark gap down to glow voltage (some 100 volts) and eventually to arc voltage (some 10 volts). At this moment, nearly the entire charging voltage (some 1,000 volts) is at the spark gaps bridged by the resistances, so that the sparking voltage of these gaps can be arrived at by giving these resistances the corresponding value. If the apparatus has only one spark gap bridged by a resistance, the magnitude of the resistance can be varied within wide limits. If a plurality of bridged spark gaps are connected in series, the bridging reactances can be differently great and so graduated that the greater part of the charging voltage arises at the spark gap offering the higher resistance and, after the sparking in this gap, arrives at the next lower resistance. Accordingly, the sparking voltage is, so to say, made to travel from spark gap to spark gap.

The apparatus embodying the invention accordingly serves two ends:

1. The distribution of potentials at the series-connected spark gaps is so controlled that the greater part of the charging voltage lies first at the unbridged gap or gaps and is passed on to the other gaps only subsequently to having sparked in the unbridged gap or gaps.

2. Sparking in the entire series of gaps no longer depends on the haphazard presence of initiating electrons at each one of the gaps at the same time.

By making a mistake in operating the apparatus, for instance by using too great a spark length or, in other words, by giving the electrodes too great a distance apart, so that sparking is prevented, a damaging of the bridging reactances may occur. Upon an interruption in sparking these reactances are caused to stand the entire charging voltage for a long time. This disadvantage can be overcome by disposing parallel to the bridging reactances protective spark gaps or automatic circuit breakers, for instance heat switches.

The sparking voltage at a gap is high as long

- as no sparking has taken place. This voltage is considerably lower for the later sparks of a series of sparks, which are favoured by the existance of discharge agents from a previous discharge.
- 5 By using a special means for initiating the first discharge, it is possible, therefore, to operate in series a plurality of spark gaps in which, otherwise, the first ignition would not take place. Another feature of the invention consists in using a 10 voltage impulse which is higher than the peak of the charging voltage in the ordinary service. According to the invention it is also possible, however, to provide that the spark gaps connected in series are first short-circuited and then opened 15 one after the other, so that the normal charging voltage suffices for producing reliable successive sparkings of the series-connected gaps.

In the spectrum analysis of metals, it has proved to be advisable to produce on the 20 surfaces of the electrodes constituted by the metals an electric equilibrium some time before the analysis proper by effecting preliminary spark discharges. The period necessarily elapsing between these preliminary spark discharges and 25 the practical use of the arrangement entails an undesired delay of the spectrum analysis. The preliminary spark discharges between one pair of electrodes can take place, however, at the same time as the spectrum analysis by means of an 30 other pair of electrodes, if at least two of the spark gaps can be used for spectrum analyses. Accordingly, while the one of these gaps is being used for spectro-analytical tests, the other can be made ready, and vice versa.

- 35 The accompanying drawing shows diagrammatically an example of a wiring diagram of the apparatus used for spectrum analysis according to the invention.

Two terminals 1 and 2 are assumed to be connected to a source of alternating current of 50 40 periods. To these terminals are connected a regulating resistance 3 and the primary winding 4 of a high-voltage transformer 5 supplying the charging voltage. Parallel to the secondary winding 6 of this transformer 5 is a spark circuit, 45 which comprises an accumulating condenser 7, a choking coil 8 and spark gaps 9 to 12 in series with these elements, the spark gaps 9-10 and 11 being analyzer gaps and 12 a rotary/interrupted. The electrodes 9, 10 and 11 consist of the alloy 50 or mixture of elements or compounds thereof, of which the percentage of quantity of the respective elements is to be analised. 13 is a high ohmic resistance parallel to 10, and 14 a condenser parallel to 11. 15 and 16 are safety spark gaps 55 parallel to the impedances 13 and 14. The spark lengths of the gaps 15 and 16 are greater than those of the gaps 10 and 11, these greater spark lengths preventing an overloading of the impedances 13 and 14. 17 is a knife-switch for short-circuiting the series of spark gaps over the contacts 18, 19 and 20 and permitting a successive opening of the spark gaps.

The device is operated by connecting a source 60 of alternating current of say 50 periods between the terminals 1 and 2 and by rotating the rotary

interrupter 12. The knife-switch 17 is at first in the position of shortcircuiting the series of spark gaps. Then this switch is opened so that the shortcircuits of the spark gaps are removed successively and the sparks will be ignited one 6 after the other during each ignition of the rotary interrupter 12. Then the knife-switch will remain opened during the entire sparking period.

I claim:

1. A device for producing electric sparks for 10 use in spectrum analysis, comprising a high voltage source, an energy accumulator connected to said source, a plurality of spark gaps connected in series to said energy accumulator for discharging said accumulator, and impedances bridging part 15 of said spark gaps.

2. A device for producing electric sparks for 20 use in spectrum analysis, comprising a high voltage source, an energy accumulator connected to said source, a plurality of spark gaps connected 25 in series to said energy accumulator for discharging said accumulator, and impedances comprising high ohmic resistances bridging part of said spark gaps.

3. A device for producing electric sparks for 25 use in spectrum analysis, comprising a high voltage source, an energy accumulator connected to said source, a plurality of spark gaps connected in series to said energy accumulator for discharging said accumulator, and impedances 30 bridging all of said spark gaps except one.

4. A device for producing electric sparks for 35 use in spectrum analysis, comprising a high voltage source, an energy accumulator connected to said source, a plurality of spark gaps connected in series to said energy accumulator for discharging said accumulator, and impedances bridging part of said spark gaps, the impedances bridging each one of said bridged spark gaps being graduated 40 in value with respect to the values of the impedances bridging each of the other spark gaps in order to obtain the greater part of the said high voltage of said energy accumulator at the spark gap offering the higher resistance, so that sparking over takes place in series in all said spark 45 gaps.

5. A device for producing electric sparks for 50 use in spectrum analysis, comprising a high voltage source, an energy accumulator connected to said source, a plurality of spark gaps connected in 55 series to said energy accumulator for discharging said accumulator, impedances bridging part of said spark gaps and means for short-circuiting said spark gaps and means for connecting them successively to the series circuit at the beginning of a series 55 of sparks.

6. A device for producing electric sparks for 60 use in spectrum analysis, comprising a high voltage source, an energy accumulator connected to said source, a plurality of spark gaps connected in 65 series to said energy accumulator for discharging said accumulator, impedances bridging part of said spark gaps, and safety spark gaps connected in parallel to said impedances for preventing an overloading of said impedances.

HEINRICH KAISER.
